UNITED STATES PATENT OFFICE.

JOHN O. HAMMELL, OF CHICAGO, ILLINOIS.

STEAM-TRAP.

1,304,563.

Specification of Letters Patent. Patented May 27, 1919.

Application filed October 19, 1917. Serial No. 197,398.

To all whom it may concern:

Be it known that I, JOHN O. HAMMELL, a citizen of the United States, and resident of Chicago, in the county of Cook and State 5 of Illinois, have invented certain new and useful Improvements in Steam-Traps, of which the following is a specification.

My invention relates to steam traps and has particular reference to an improvement 10 on the construction shown in my application, Serial No. 193,477, filed Sept. 27, 1917.

One of the difficulties encountered in the operation of steam traps of the float-valve type is that of the fouling or clogging of the 15 valve by scale and particles of solid matter carried along by the condensed steam. Particularly in high pressure traps the size of the water outlet must be relatively small and the likelihood of interference with the operation of the valve is increased. To screen 20 the valve is ineffective and neither is it practical to place a screen in the inlet pipe as the pipe will very shortly become clogged. To obviate the difficulty I provide a relatively 25 large lateral chamber at the inlet, place a screen at the junction of the chamber and the casing proper and provide a blow-off contiguous to the screen. The size of the chamber is such that the screen or outlet 30 cannot become clogged. Furthermore, the construction is such that the screen supporting member serves as a guide for the valve stem at its upper end. In the constructions heretofore proposed the stem has been guided in the inlet pipe. This interfered materially with the effective size of the 35 pipe.

The invention will be more readily understood by reference to the accompanying 40 drawing, wherein,

Figure 1 is a vertical, sectional view through a steam trap constructed in accordance with my invention;

Fig. 2 is a plan view thereof;

Fig. 3 is a sectional view on the line 3—3 of Fig. 1, and,

Fig. 4 is a plan view of the screen and its support.

In the drawings it will be seen that the 50 trap includes a casing having lower and upper parts 10, 11, which are joined by the bolts 12, engaging apertured lugs on the two parts of the casing. Mounted within the casing is the float-valve 13, which is guided at its upper end by means of the stem 14. The lower end is guided by means of the

valve stem 15, which is held within the cylindrical projection 16, from the valve member 17. The water outlet pipe is connected to the nipple 18, the water escaping past 60 the valve stem 15, through the opening 19. By reason of the fact that the cylindrical portion 16, projects upwardly from the bottom of the casing a considerable distance, the outlet from the casing will be above the 65 floor thereof and sediment such as scale and particles of solid matter which have settled to the floor of the casing will not be drawn into the outlet. It is well known that the discharge of liquid from a vessel through a 70 central outlet and particularly a vessel having a round bottom, tends to set up a whirling motion in the liquid. Such motion of the liquid stirs up and prevents the deposit of particles of solid matter and the particles 75 are caused to be discharged through the outlet. Furthermore, it is known that the effect of such whirling motion is to cause a vortex at the outlet and materially reduce the discharge capacity. I avoid both of 80 these disadvantages by providing radial walls or webs 20, which project inwardly of the casing at a point below the float, three of such webs being shown. These 85 serve to prevent the whirling of the water and obviate the difficulties referred to. As the water of condensation enters the casing together with any sediment or scale, the latter is thrown to the sides of the casing by contact with the top of the float and descends by gravity along the walls to the 90 sloping body. When the valve lifts to discharge the water there is no whirling action and the sediment is not drawn into the outlet. It rests in the groove 21, which surrounds the valve casing and finally is drawn 95 into the recess 22, located at one side of the outlet and below the same. A drain or blow-off pipe 23, is connected with the recess 22, and when the valve controlling the 100 same is opened the sediment is discharged therethrough. Thus a simple means is provided for keeping the valve free from particles which would tend to clog the same and interfere with the operation.

As a means for preventing the entrance of solid matter into the casing, I provide the novel arrangement shown in Fig. 1, in which a chamber 24, is formed at the inlet, the chamber being formed by casting a hollow, 110 hemispherical projection on the upper half 11 of the casing. At the lower end of the

chamber 24, I mount a screen 25, which is secured to and supported by a circular frame 26, having a transverse cross bar 27. An aperture 28, at the center of the cross bar 27, provides a guide for the stem 14. Screws 29, are provided for securing the frame or screen in place. It will be noted that the screen is slightly inclined toward a blow-off outlet 30, in order to assist in freeing 10 the surface of the screen from any deposits.

The size of the chamber and of the screened area is such that it is not likely to become clogged so as to interrupt the action of the trap. The provisions described for 15 preventing the entrance of scale and disposing of the same if particles should enter the casing insure the uninterrupted action of the device under all conditions.

The exact form and arrangement shown 20 are not essential and may be varied without departure from the spirit of my invention.

I claim:

1. In a steam trap, the combination of a casing having an inlet opening, the opening

being materially enlarged at the point of entrance to the casing, a screen disposed across the opening, a blow-off opening horizontally arranged at a point immediately above said screen, the screen being inclined downwardly toward said opening, substantially as described. 25 30

2. In a steam trap, the combination of a casing having a hollow projection at its upper end, the projection providing an inlet opening and a lateral blow-out opening, a screen extending across the inlet opening at a point immediately below the blow-out opening, a support for said screen, a float in said casing, the upper end of the float being guided by said support, the screen being 40 inclined downwardly toward said blow-out opening, substantially as described.

Signed at Chicago, Illinois, this 15th day of October, 1917.

JOHN O. HAMMELL.

Witness:

DAVID JOHNSTONE.
